ANTON WEBER AND CLEMENT LAMBERT, OF ELIZABETH, NEW JERSEY.

CORDAGE-SPINNING MACHINE.

SPECIFICATION forming part of Letters Patent No. 404,137, dated May 28, 1889.

Application filed March 30, 1888. Serial No. 268,995. (No model.)

To all whom it may concern:

Be it known that we, ANTON WEBER and CLEMENT LAMBERT, of Elizabeth, in the county of Union and State of New Jersey, have invented a new and useful Improvement in Cordage-Spinning Machines, of which the following is a full, clear, and exact description.

This invention relates to a cordage-spinning machine; and it consists in an improvement thereon whereby the operation of the machine is automatically stopped if the cord breaks, and the machine cannot be started until the bobbin upon which the twisted cord is wound is securely mounted upon its spindle.

The invention will be set forth in the following description, and pointed out in the claims.

Reference is to be had to the accompanying drawings, forming a part of this specification, in which similar figures of reference indicate corresponding parts in all the views.

Figure 1 is a side view of a portion of the cordage-spinning machine, partly broken away and in section. Fig. 2 is a plan view on line $x-x$ of Fig. 1. Fig. 3 is a plan view of a detail, with parts broken away, showing a portion of the spindle on which the bobbin is mounted and the safety device for holding the spindle in place. Fig. 4 is a detail plan view of the bracket at the end of the capstan-tube, with parts broken away, and a portion of the automatic stopping device. Fig. 5 is an end view, with parts broken away, and in cross-section of the machine looking from right to left in Fig. 1. Fig. 6 is an end view, with parts broken away, of the machine looking from left to right in Fig. 2. Fig. 7 is a detail view, with parts broken away, of a bobbin safety device; and Fig. 8 is a detail view of the spindle-stop shown in Figs. 3 and 6.

1 indicates the framing of a portion of a well-known form of cordage-spinning machine, having mounted therein the usual driving mechanism, consisting of the main shaft 2, having bevel-gearing 3 at one end thereof connected by a shaft, 4, with a fast pulley, 5, and a loose pulley, 6, which are driven by means of a band, 7, leading to any suitable power. The main shaft 2 has at its other end a pulley, 8, connected by a band, 9, with a pulley, 10, in which is mounted the well-known

capstan-tube receiving the cord 11 from the nippers and condenser. (Not shown.)

The twisting and winding mechanism is of the usual construction, and may be briefly described, as follows:

12 indicates the flier, and 19 its operating-pulley.

14 is a sliding shaft passing through the sleeve 15 of bracket 16 and through the sleeve 17, carrying the bobbin 13 to the outer head, 20, of the flier.

18 is the pulley on the bobbin-sleeve 17. The pulleys 18 and 19 are driven by belts 21 from the main shaft 2.

In order to shift the driving-belt 7 from the fast pulley 5 to loose pulley 6, and vice versa, the following mechanism is employed: At the end of the frame 1 is mounted, in brackets 23, a transverse sliding bar, 24, having pins 25 projecting at right angles thereto on either side of the driving-belt 7. Any suitable shifting-lever may be connected with bar 24 to start and stop the machine by hand.

To automatically stop the machine when the cord breaks, the following mechanism is connected with the belt-shifting mechanism: The sliding bar 24 is provided with a depending arm, 25', having an oblong slot, 26, which is engaged by a pin, 27, on the lower end of a lever, 28, mounted on a shaft, 31, from which extends an arm, 29, having counter-weight 30. The shaft 31 extends lengthwise through the frame 1, and is provided with a depending arm, 32, which connects at its lower end by a pin, 40, with the inner shoulder, 42, of a lever, 35, pivoted to a bracket, 36, on the frame 1.

Mounted in adjustable brackets 37 on the frame 1 is a shaft, 38, which has a depending arm, 39, with a pin, 33, engaging a notch, 34, of the lever 35. On the shaft 38 is also mounted a lever, 43, extending horizontally therefrom, and pivotally connected at its end with a vertical rod, 44, eccentrically pivoted to an arm, 45, pivoted to a bracket, 46, on the frame 1 adjacent to the pulley 10, in which is mounted the capstan-tube, through which the cord passes from the nippers and condenser. (Not shown.) The shaft 38 carries at its end beyond lever 43 the common and well-known shifter-arm, which acts on the

drawing-head of the well-known hemp-feeding mechanism to shift it and instantly stop the hemp-feeding mechanism. The pivotal connection 47 of the rod 44 with the arm 45 is slightly to the left of the pivotal point 48 of the arm 45, so that the arm 45 gently bears against the cord 11. The lever 43 is provided with a spring 49, secured at its lower end to a staple, 50, in the floor. The relative position of the pivotal points 47 and 48 to each other is such that the tension of the spring 49 does not exert a great force to draw the arm 45 against the cord 11. The arm 45 is prevented from falling backward or away from the cord 11 by means of the pin 45'.

The operation of automatically stopping the machine in case the cord breaks will now be described.

Upon the cord 11 breaking, the arm 45, which gently bears against the cord 11, will drop over toward the left, and by means of the action of the spring 49 the lever 43 will be pulled down, thereby causing the shaft 38 to be turned, and with it the arm 39, which throws the latter outward, and by means of the pin 33 lifts the lever 35, releasing the notch 42 from the pin 40. By this means the arm 32, upon which the pin 40 is mounted, is permitted to have free movement, and being mounted on the shaft 31 is rotated with it by means of the counterweighted lever 29, which drops downward and swings the arm 28 to one side, and by means of the connection with the pin 27 in the oblong slot 26 pushes the arm 25' to one side and carries with it the sliding bar 24, thereby, on account of the pins 25 projecting from the sliding bar 24, shifting the driving-band 7 from the fast pulley 5 to the loose pulley 6 and causing the driving mechanism to stop.

It being often necessary to remove the winding-bobbin 13, and there being liability to accident owing to careless replacing of the bobbin, the following device is employed: To remove the bobbin 13, the shaft or spindle 14 is slid laterally until it is disconnected from the bobbin 13. It has been found that in replacing the bobbin the shaft 14 has been hastily and carelessly slid back, so that its end did not slip into its bearing 20, and the machine then being started an accident ensued. In order to prevent the machine from being started until the bobbin is securely mounted on its spindle, the following device is employed: A slide, 51, provided with a handle, 52, is mounted in the bracket 16. When the rod or spindle 14 has been pushed into place and the slide 51 dropped down over the outer end of the spindle 14, the latter is thereby held from being drawn out.

To one of the brackets 23 is pivoted a lever, 53, formed with an angular portion, 54, and connected at its other end, 55, with a rod, 56, having a hooked end, 57, adapted to engage the handle 52. When the machine is in operation, the lever 53, the rod 56, and the slide or guard-piece are in the position shown in

Fig. 6, the lever 53 being out of contact with either of the pins 25. Upon the driving-belt 7 being shifted to the loose pulley 6 and the machine stopped and it is desired to remove the bobbin 13, the slide or guard 51 is raised, carrying with it the rod 56, and raising the lever 53, so that its angular portion 54 is brought against the outer pin, 25, which has been carried to the right by the movement of the slide-bar 24 when the machine has been stopped, the position being shown in Fig. 7. The lever 53 will be held in engagement with the pin 25 by means of the slide or guard 51 resting on the spindle 14, as shown in Fig. 1. By this means it will be seen that the machine cannot be started until the lever 53 is released from the pin 25. This latter can only be effected by pushing in the spindle 14 until the slide or guard 51 is permitted to drop past the end of the spindle 14. The bobbin will then have been securely mounted on its spindle, and the machine may then be started by pushing the bar 24 to the left and shifting the driving-belt 7 to the fast pulley 5. By means of this invention upon the breaking of the cord the machine will be automatically stopped, and cannot be started until the bobbin is securely mounted in place.

Having thus described our invention, what we claim as new, and desire to secure by Letters Patent, is—

1. In a cordage-spinning machine, a belt-shifting mechanism, a counterweighted crank-shaft which moves the belt-shifting mechanism in one direction to shift the driving-belt from the fast to the loose pulley, a spring-actuated latching and tripping mechanism connected with and holding the counterweighted crank-shaft, an arm pivoted adjacent to the capstan-tube, adapted to normally bear against the cord, and a rod connecting said arm with the spring-actuated tripping mechanism, substantially as described.

2. In a cordage-spinning machine, a belt-shifting mechanism having a depending arm, a counterweighted crank-shaft having a depending arm pivotally connected with said depending arm on the belt-shifting mechanism, a shaft having a depending arm with a pin, a pivoted lever beneath which said pin projects, having a notch, a second arm depending from the counterweighted crank-shaft and provided with a pin engaged by said notch, a lever on the second shaft with retracting-spring, and an arm pivoted adjacent to the condenser, connected with said second shaft, and adapted to bear against the cord, substantially as described.

3. In a cordage-spinning machine, the combination, with sliding bar 24, having pins 25 projecting by driving-belt 7, and the depending arm 25', with slot 26, of the shaft 31, having depending arm 28, with pin 27, engaging slot 26, arm 29, with counter-weight 30, depending arm 32, having a pin, 40, shaft 38, with depending arm 39, having a pin, 33, pivoted arm 35, having notch 42 engaging pin

40 and shoulder 34 engaging pin 33, horizontal lever 43 on shaft 38, with retracting-spring 49, and arm 45, pivoted adjacent to pulley 10 and adapted to bear against the cord, rod 5 44, connecting arm 45 with lever 43, and stoppin 45', adjacent to arm 45, substantially as described.

4. In a cordage-spinning machine, the combination, with the belt-shifting mechanism 10 and the sliding detachable spindle of the winding-bobbin, of a sliding plate extending over the end of the spindle, a shouldered pivoted lever adjacent to the belt-shifting mechanism to engage the same, and a vertical rod 15 connecting the shouldered lever with the sliding plate, substantially as described.

5. In a cordage-spinning mechanism, the combination, with the belt-shifting mechanism, of a shouldered lever adapted to engage 20 one of the belt-shifting pins, a sliding plate extending over the end of the removable bobbin-spindle, and a rod connecting the sliding plate with the shouldered lever, substantially as described.

25 6. In a cordage-spinning machine, the sliding plate 51, having handle 52, the supporting-bracket 16, having sleeve 15, the remov-

able spindle 14, the end of which is supported in said sleeve, rod 56, having a hooked end engaging handle 52, lever 53, pivoted to bracket 30 23 and having shoulder 54, and a belt-shifter having pins 25, substantially as described.

7. In a cordage-spinning machine, the removable bobbin-spindle, a vertically-movable plate extending over the end of spindle, a lever adjacent to the belt-shifting pins, and a rod connecting said lever and plate, in combination with the belt-shifting mechanism provided with said pins, a counterweighted crank-shaft connected with said belt-shifting mech- 40 anism, a spring-actuated latching tripping mechanism which holds and sets free the counterweighted crank-shaft, a pivoted arm adapted to bear against the cord, and a rod connecting said arm with the spring-actuated tripping mechanism, substantially as de- 45 scribed.
